John C. Johnson
Attorney.

UNITED STATES PATENT OFFICE.

GEORGE C. DAY, OF NINEVEH, PENNSYLVANIA, ASSIGNOR OF ONE-HALF TO
GEORGE M. CONDIT, OF SAME PLACE.

ALARM-LOCK.

SPECIFICATION forming part of Letters Patent No. 402,413, dated April 30, 1889.

Application filed October 11, 1888. Serial No. 287,804. (No model.)

To all whom it may concern:

Be it known that I, GEORGE C. DAY, a citizen of the United States of America, residing at Nineveh, in the county of Greene and State of Pennsylvania, have invented certain new and useful Improvements in Alarm-Locks; and I do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

My invention relates to certain new and useful improvements in alarm-locks, the object thereof being to provide a lock or latch by means of which, when the knob-spindle is turned, an alarm will be sounded, this lock or latch also being provided with means whereby the latch can be thrown out of connection with a bolt operating the same and operated by the knob-spindle, the lock also being provided with means whereby the alarm can be held so as to be inoperative when desired; and my invention consists in the construction and combination of the parts, as will be hereinafter fully set forth, and specifically pointed out in the claims.

In the accompanying drawings, Figure 1 is a side view of an alarm-lock constructed in accordance with my invention, a portion of the outer casing being broken away to better show the interior construction. Fig. 2 is a sectional view taken through the line $x-x$ of Fig. 1. Figs. 3 and 4 are detail perspective views.

A refers to the lock-casing, which is provided with a key-hole, a , through which the key for operating the locking-pawl is inserted. The lock-casing is also provided with a spindle, b , having a slot through which the key enters for operating the latch B , this spindle being held from accidental rotation by a spring, b' , which bears upon a flattened portion of the spindle, preventing rotation.

The latch B is pivoted to the lock-casing and provided with an arm, c , which is pivoted thereto and passes through a stud, c' , projecting from the lock-casing. Between the stud

c' and latch B the arm c is encircled by a spring, by which the latch is thrown out of the casing, and the end of the arm extends downwardly, so as to be engaged by the key when it is desired to throw the latch by means of a key.

D and D' refer to bifurcated bolts, the bifurcated ends of which are provided with hooks d d , with which the arms e e of the hub, through which the knob-spindle passes, will engage, in order to draw the bolts toward each other, thereby retracting the latch and actuating the bell. These bolts D and D' are held normally apart by a spring, F , which bears upon shoulders formed on the bolts. The bolt D' is held in position, so as to move in line to and from the knob by lugs f f , which overlap the straight portion thereof.

The upper portion or end of the latch B is bifurcated, and between the arms thereof the end of the bolt D passes, this end of the bolt being provided with a transverse pin, g , which engages with the latch, the portion with which it engages being curved, as shown. The bolt D is provided with a pin, G , the upper portion of which is flat and passes through a slot in the lock-casing. The stem g' of the pin is encircled by a spiral spring which bears upon washers moving upon the stem g' , and the lower end of the stem of this pin is secured within a tapered recess, h , formed in the bolt D , and is held within said tapered recess by a pin which engages with the notched end, so as to permit the rotation of the pin G . When it is desired to throw the bolt D out of engagement with the latch, the pin G is drawn upwardly and turned so that the head thereof will lie across the slot in the casing, thus holding the bolt up out of engagement with the latch, as shown in dotted lines, Fig. 1. When the bolt D is out of engagement with the latch B , said latch can only be operated by the use of a key.

The bolt D' at its end is provided with an inclined notch or ratchet, i , and adjacent to this ratchet the lower end of the bolt is cut away at an incline, as shown at i' . The upper end of the bolt has an inclined notch, k , with which a dog, K , engages. This dog K is pivoted to the lock-casing and provided with

a catch or hook, k' , which engages with the inclined notch k to hold the bolt D' out of engagement with the bell-hammer.

Immediately beneath the end of the bolt D' is an inclined bar or plate, l , upon which the arm m of the bell-hammer M rides. The bell-hammer M is drawn downwardly by a spring to strike the bell N when released. When the bolt D is thrown out of engagement with the latch B and the knob of the spindle turned, an alarm will be sounded without actuating the latch, and when it is desired to adjust the lock so that the spindle can be turned without sounding the alarm the dog K is turned to engage the inclined notch k , which will prevent the bell-hammer being actuated. When the parts are in the position shown in full lines in the accompanying drawings and the spindle turned, the latch will be retracted and an alarm sounded.

If desirable, the casing may be extended to cover the bell.

I am aware that prior to my invention it has been proposed to provide an alarm-lock with a bell and hammer, so that an alarm will be sounded when the knob is turned, and I do not claim such construction broadly as my invention; but

30. What I claim as new, and desire to secure by Letters Patent, is—

1. The combination, in an alarm-lock, of the bifurcated bolts D and D' , having hooks which engage with the arms of the knob-spindle, a spring for holding said bolts apart and in contact with the arms of the knob-spindle, a pivoted latch, B , operated by one of the bolts, and a bell-hammer actuated by the other bolt, substantially as shown, and for the purpose set forth.

2. The combination, in a lock having bolts D and D' , and a bell-hammer actuated by one of said bolts, of a pivoted latch having an arm, c , stud c' , through which said arm passes, and a spiral spring for throwing said latch outwardly, the upper portion of said latch being bifurcated to engage with a pin, g , carried by the bolt D , substantially as shown, and for the purpose set forth.

3. The combination, in a lock, of the bifurcated bolt D , having hooks $d d$, which engage with arms on the knob-spindle, and a pin, G , extending through the lock-casing and engaging with the bolt for elevating the end thereof to throw the same out of engagement with the latch, substantially as shown, and for the purpose set forth.

4. The combination, in an alarm-lock, of the bolt D' , adapted to be actuated by the knob-spindle, said bolt being provided with an inclined notch, k , and a pivoted dog, K , provided with a hook to engage the notch k , to hold said bolt out of engagement with the arms of the knob-spindle, so that the alarm will not be actuated, substantially as shown, and for the purpose set forth.

5. The combination, in an alarm-lock, of the bell, spring-actuated bell-hammer, and arm m , the bolt D' , having inclined portions i and i' and an inclined plate, l , over which the arm m rides to release the same from the notches formed on the end of the bolt D' , substantially as shown, and for the purpose set forth.

6. The combination, in an alarm-lock, of the bolts D and D' , constructed substantially as shown, and adapted to be operated by a single knob-spindle having arms $e e$, said bolts being provided with a common spring, F , guide-lugs $f f$, notches i , i' , and k , formed in the bolt D' , a dog, K , for engaging with one of said notches, and a spring-actuated bell-hammer with which the bolt D' engages, a pin, G , extending through the lock-casing and engaging with the bolt D to hold the same out of engagement with the latch, and a latch, B , carrying a pivoted arm encircled by a spring, with which a key can engage for operating said latch independent of the knob-spindle, substantially as shown, and for the purpose set forth.

In testimony whereof I affix my signature in presence of two witnesses.

GEORGE C. DAY.
